UNITED STATES PATENT OFFICE.

ARNO W. ROBERTSON, OF MOUNT VERNON, NEW YORK, ASSIGNOR TO GEORGE R. SWART & COMPANY, INC., OF NEW YORK, N. Y., A CORPORATION OF NEW YORK.

PAPER LIFT.

1,411,520.

Specification of Letters Patent.

Patented Apr. 4, 1922.

Application filed April 22, 1921. Serial No. 463,659.

To all whom it may concern:

Be it known that I, ARNO W. ROBERTSON, a citizen of the Dominion of Canada, and a resident of the city of Mount Vernon, in the 5 county of Westchester and State of New York, have invented certain new and useful Improvements in Paper-Lifts, of which the following is a specification, reference being made to the accompanying drawings, forming a part thereof.

My invention relates generally to machines for feeding separate sheets to a printing press or other like machine, and I have devised my improved mechanism in connection with an automatic sheet-feeder in which the individual sheets are automatically separated from a feathered or fanned out bank resting on the feed-board and are then advanced to a suitable conveyor mechanism 15 which will carry such sheets, one by one, to the printing-press or other machine.

The objects of my invention are, among other things, to embody in a sheet-feeder of this type, an improved paper-lift upon 20 which the vertical pile of superimposed sheets may be supported after being transferred from the loading truck to a movable table which is a part of the lift itself, and to provide suitable actuating means whereby 25 such paper-lift with the vertical paper pile thereon may be elevated to form a rearward extension of the feed-board while at the same time by the elevation of the component parts of the lift, such vertical pile may be tilted 30 forwardly in such manner as to feather or fan out such pile to the required extent to 35 form a fanned out bank on the rear end of the feed-board beneath the sheet-feeding devices, and also overlapping on the rearward 40 extension thereof when the paper-lift has been fully elevated.

A further object of my invention is to simplify the construction of such paper-lifts with the devices for operating same so that 45 they may be readily raised and lowered in an efficient manner to the end that the pile of sheets may be safely loaded on the lift and then spread out into the necessary fanned out bank without disturbing the lateral alignment of the pile ready to be acted 50 on by the automatic sheet-feeding devices for which my improved device has been particularly designed.

Further advantages and functions will

hereinafter be more particularly set forth, 55 and a preferred embodiment of my invention is illustrated in the accompanying drawings in which—

Fig. 1 is a side elevation of my improved paper-lift attached to the rear end of the 60 feed-board of an automatic sheet-feeder with which the printing-press is ordinarily equipped, the frame of the press being broken away;

Fig. 2 is an enlarged diagrammatic view 65 showing the action of the device to fan the sheets of paper from the pile ready to be finally separated and advanced to the press by the sheet-feeding mechanism;

Fig. 3 is an enlarged fragmentary sectional side view showing the manner of loading the table of a sheet-feeder with a pile of paper sheets;

Fig. 4 is a detail sectional plan view showing the table and its supporting members 70 in the feeder, the section being taken on the line 4—4 in Fig. 3 looking in the direction of the arrow; and

Fig. 5 is a plan view of my device, the printing cylinder and sheet-feeding mechanism being omitted, together with a diagrammatic illustration of the electrical connections for the actuating motor.

Similar numerals refer to similar parts throughout the several figures.

Referring to the drawings, 6 designates the cylinder of a printing press or other machine and 7 is the usual feed-board mounted on the side frames 8, the feed-board 7 serving to support the forward part of the 90 fanned out bank of sheets which are acted on by the sheet-feeding and conveyor mechanisms to carry the separate sheets over the board 7 to the cylinder 6. Slidably mounted above the feed-board 7 is the main head 9 carrying the sheet-feeding devices proper 95 which extend rearwardly as shown in Figs. 1 and 2. These feeding devices comprise the combing rolls 10 (only one being shown) carried by the arm 11 loosely mounted on the shaft 12 carried by the head 9, such combing rolls being rotated by the train of gears 13 actuated by the reciprocating rack 14 as shown in Figs. 1 and 2. Extending forwardly from the head 9 are two bars 15 (only 105 one being shown in Fig. 1) upon which the sheet-conveyor mechanism is supported by which the individual sheets after being sep-

arated and advanced by the combing rolls 10 are forwarded over the feed-board 7 to the printing cylinder 6. Since these are common forms of sheet-feeder construction and 5 are well known in the art, they are not shown in detail in the drawings as they do not in themselves constitute any part of my improvement.

At the rear end of the feed-board 7 I rotatably mount the transverse shaft 16 in the 10 brackets 17 and 18 secured to the rear edge of the feed-board 7 and the side frames 8. The shaft 16 carries a series of rollers 19 over which pass the conveyor tapes 20 upon 15 which the forward portion of the pile is advanced over the feed-board 7. Mounted on the shaft 16 by brackets 21 is the depending swinging table-board 22, the board 22 being adapted to swing upwardly and downwardly 20 on the shaft 16 as its axis. The lower or rearward end of the table-board 22 has secured thereto two brackets 23 and 24 as shown in Fig. 4 in which the transverse shaft 25 is rotatably secured. The shaft 16 carries tape-rollers 26, while the shaft 25 has 25 affixed thereto rollers 27 around which the usual conveyor tapes 28 pass to advance the bank of sheets when the table-board 22 is swung upwardly to its raised forwardly inclined position as shown in Fig. 2.

Pivoted to the outer ends of the shaft 25 are two table-carrier bars 29 and 30 secured to this shaft by forked ends 31 and 32 respectively; within the forked ends 31 and 32 are 35 two pulleys 33 and 34 respectively each journalled on the shaft 25 as shown in Fig. 4. The outer forked ends 35 and 36 of the carrier bars 29 and 30 carry pulleys 37 and 38 respectively as shown in Figs. 4 and 5. 40 Preferably the two carrier bars 29 and 30 each has formed therein two parallel slots 39 and 40, each set being located in transverse alinement to contain the depending flanges 41 and 42 of the two transverse angle-irons 43 and 44 secured to the bottom of the table 45 upon which the pile of paper 46 is loaded. When the flanges 41 and 42 are set down in the slots 39 and 40 as shown in Fig. 1 the table 45 with the pile of paper 46 is securely 45 mounted upon the carrier bars 29 and 30 as a pile-support, and is directly movable on and with such bars when raised and lowered in conjunction with the table-board 22.

Means are provided to swing the depending 55 table-board 22 and the table 45 affixed to the carrier bars 29 and 30 as a pile-support jointly whereby the vertical pile 46 is tilted forwardly to produce the required fanned out bank extending forwardly on the feed-board 7 beneath the combing rolls 10: In the embodiment shown two side-bars 47 and 48 are adjustably secured to the side frames 8 by the set-screws 49 or other suitable means. These bars project rearwardly from the side frames 8 substantially in the plane of the

feed-board 7 as shown in Figs. 1 and 3. The rear ends of the side-bars 47 and 48 carry the brackets 50 and 51 respectively to which is secured the cross brace 52; extending upwardly from brackets on the brace 52 are 70 two supporting rods 53 and 54 respectively which are attached by any suitable means (not shown) to cross-beams or ceiling fixtures in the press room in which my improvement is installed, so as to secure the ends of such bars 47 and 48 in the necessary elevation which may be adjusted when desired. Pivoted to the ends of the brace 52 at either side of the machine are two collars 55 and 56 (Fig. 5) to which flexible carrier cables 80 or ropes 57 and 58 are respectively secured which carrier cables are similer in construction and operation. Slidably secured on the side bars 47 and 48 are brackets 59 and 60 in which the winding shaft 61 is journalled as 85 shown in Fig. 5, the shaft 61 having affixed thereto two winding drums 62 and 63 of like size at either side of the machine. The carrier cable 57 passes downwardly around the pulleys 37 and 33 and then upwardly to the 90 drum 62 to which it is secured, while the cable 58 passes in like fashion around the pulleys 38 and 34 and then upwardly to the drum 63 to which it is likewise secured as shown in Figs. 1 and 5. The drum 62 and 63 95 are rotated in either direction preferably by the electric motor 64 mounted on the support 65 secured to the side-bar 47 through connecting gears 66, the worm 67 and worm gear 68 secured to the end of the winding shaft 100 61. In Fig. 5 I have shown a diagram of the electrical connections with the generator 69 and pole-changing switch 70 by which the motor 64 may be rotated in either direction as required.

Referring to Fig. 3, I have shown a preferred means of loading the pile 46 on the table 45 on the carrier bars 29 and 30: The table 45 is supported by the angle irons 43 and 44 on the vertically movable platform 71 110 of the truck 72 mounted on wheels 73 and moved by the handle 74. As shown the platform 71 is raised and lowered by the screw shafts 75 threaded in brackets 76 secured in the floor 77 of the truck, such shafts 75 having the worm gears 78 operated by worms 79 on the operating shaft 80 which is rotated by the crank 81. By these devices the table 45 on the platform 71 may be raised and lowered as required, Fig. 3 showing same raised 120 with the depending flanges 41 and 42 above the slots 39 and 40 and about to be lowered therein.

Pivoted on the ends of the shafts 25 are two swinging supports 82 (only one being 125 shown), while similar supports 83 depend from the shafts of the pulleys 37 and 38. These four supports act to rigidly support the carrier bars 29 and 30 when the heavy pile 46 is resting thereon and to prevent the 130

pulleys 33, 34 and 37, 38 from undesirably contacting with the floor 84 from the elasticity of the carrier cables 57 and 58 or for any other cause. Such supports 82 and 83 also serve as guides to keep the cables 57 and 58 on the pulleys during the raising and lowering movements of the table-board 22 and table 45.

The operation of my paper-lift is shown in Figs. 1, 2 and 3 and is substantially as follows: The truck 72 with the table 45 resting on the raised platform 71 is pushed in between the two carrier bars 29 and 30 into the position shown in Fig. 3. The crank 81 is then turned to lower the platform 71 which allows the depending flanges 41 and 42 of the table 45 to be lowered to, and rest on, the carrier bar slots 39 and 40 as shown in Fig. 1 whereby the pile 46 is supported on the bars 29 and 30. The truck 72 is then withdrawn and the motor 64 is actuated to cause the winding drums 62 and 63 simultaneously to shorten the carrier cables 57 and 58. The initial shortening of these cables will cause the table 45 and table-board to be swung to the right on the shaft 16 as a pivot and away from the floor 84, the general direction being indicated by the dotted arrow shown in Fig. 1. When the table-board 22 and table 45 are raised to their expanded obtuse-angled position shown in dotted lines in Fig. 1, the pile 46 will have tilted forwardly so that such pile will have the outline substantially as indicated by the dotted line 85, the individual sheets being feathered or fanned out in a bank as shown in Fig. 2, whereby the combing rolls 10 may separate and advance the individual sheets as in "continuous feeders." When the pile 46 is depleted from the table 45 and table-board 22, the motor 64 is reversed to unwind the carrier cables 57 and 58 from their respective drums 62 and 63 and the parts take the position shown in full lines in Fig. 1 ready for receiving a fresh pile of paper from the loading truck 72.

Many variations and modifications may be made in the detailed construction of my improved paper-lift and in the arrangement of the mechanisms by which the component parts of the lift are raised and lowered without departing from the principles of my invention as herein disclosed. Therefore I do not restrict myself to the specific structural features or arrangements which I have here-
55 in illustrated and described.

I claim as my invention:

1. In a paper-lift, a frame, a table-board pivoted thereto, pile-supporting means pivoted to the table-board, and means to raise and lower said table-board and supporting means on said pivots.

2. In a paper-lift, a frame, a table-board pivoted thereto, pile-supporting means pivoted to the lower edge of the table-board,

and means to raise and lower said table-board and supporting means on said pivots. 65

3. In a paper-lift, a frame, a table-board pivoted thereto, pile-supporting means pivoted to the table-board, and means to raise and lower said table-board and supporting means jointly and simultaneously on said pivots. 70

4. In a paper-lift, a frame, a table-board pivoted thereto, pile-supporting means pivoted to the lower edge of the table-board, 75 and means to raise and lower said table-board and supporting means jointly and simultaneously on said pivots.

5. In a paper-lift, a feed-board, a depending table-board pivoted to said feed-board, 80 separable pile-supporting means pivoted to the lower edge of the table-board, and means to raise said table-board and pile-supporting means on said pivots to form a rear extension of said feed-board. 85

6. In a paper-lift, a feed-board, a depending table-board pivoted to the rear transverse edge of said feed-board, separable pile-supporting means pivoted to the lower edge of the table-board, and means to raise said 90 table-board and pile-supporting means on said pivots to form a rear extension of said feed-board.

7. In a paper-lift, a feed-board, a depending table-board pivoted to said feed-board, 95 separable pile-supporting means pivoted to the lower edge of the table-board, and means to raise said table-board and pile-supporting means jointly and simultaneously on said pivots to form a rear extension of said feed- 100 board.

8. In a paper-lift, a feed-board, a depending table-board pivoted to the rear transverse edge of said feed-board, separable pile-supporting means pivoted to the lower edge 105 of the table-board, and means to raise said table-board and pile-supporting means jointly and simultaneously on said pivots to form a rear extension of said feed-board.

9. In combination with automatic sheet- 110 feeding devices, a feed-board, a table-board pivoted thereto, sheet pile-supporting means pivoted to the table-board, and means to jointly raise both table-board and pile-supporting means to fan out the pile over said 115 feed-board beneath said sheet-feeding devices.

10. In combination with automatic sheet-feeding devices, a feed-board, a table-board pivoted thereto, sheet pile-supporting means 120 pivoted to the table-board, and means to jointly raise both table-board and pile-supporting means on their pivots to fan out the pile over said feed-board beneath said sheet-feeding devices. 125

11. In combination with automatic sheet-feeding devices, a feed-board, a table-board pivoted thereto, sheet pile-supporting means

11
pivoted to the table-board, and means to jointly raise both table-board and pile-supporting means on their pivots to fan out the pile forwardly over said feed-board beneath 5 said sheet-feeding devices.

12. In combination with automatic sheet-feeding devices, a feed-board, a table-board pivoted thereto, sheet pile-supporting means transversely pivoted to the lower edge of 10 said table-board, and means to jointly raise both table-board and pile-supporting means on their pivots to fan out the pile forwardly over said feed-board beneath said sheet-feeding devices.

13. In a paper-lift, a swinging table-board, pile-supporting means pivoted thereto, means to raise and lower jointly said table-board and supporting means, and independent means to hold said pile support 20 when said actuating means are lowered.

14. In a paper-lift, a swinging table-board, pile-supporting means pivoted thereto, means to raise and lower jointly said table-board and supporting means, and separate members loosely journaled on said supporting means to hold said pile support when said actuating means are lowered.

15. In a paper-lift, a feed-board, a depending table-board pivoted to said feed-board, table-supporting means pivoted to the lower edge of the table-board, a pile table 30 detachably mounted on said supporting means, and means to raise both table-board and supporting means on the pivots to fan out the pile and beneath said sheet-feeding devices.

out the pile over said feed-board, table-board 35 and table.

16. In a paper-lift, a feed-board, a depending table-board pivoted to said feed-board, table-supporting means pivoted to the lower edge of the table-board, a pile table 40 detachably mounted on said supporting means, and means to jointly and simultaneously raise both table-board and supporting means on the pivots to fan out the pile over said feed-board, table-board and table. 45

17. In combination with automatic sheet-feeding devices, a feed-board, a depending table-board pivoted to said feed-board, table-supporting means pivoted to the lower edge of the table-board, a pile table 50 detachably mounted on said supporting means, and means to raise both table-board and supporting means on the pivots to fan out the pile over said feed-board, table-board and table and beneath said sheet-feeding devices. 55

18. In combination with automatic sheet-feeding devices, a feed-board, a depending table-board pivoted to said feed-board, table-supporting means pivoted to the lower edge of the table-board, a pile table 60 detachably mounted on said supporting means, and means to jointly and simultaneously raise both table-board and supporting means on the pivots to fan out the pile over said feed-board, table-board and table and beneath 65 said sheet-feeding devices.

ARNO W. ROBERTSON.
